UNITED STATES PATENT OFFICE.

CLAIR L. FARRAND, OF FOREST HILLS, NEW YORK; ERNEST ROSS, OF EAST ORANGE, AND PAUL F. GODLEY, OF UPPER MONTCLAIR, NEW JERSEY; SAID ROSS AND SAID GODLEY ASSIGNORS TO FARRAND MFG. CO. INC., OF LONG ISLAND CITY, NEW YORK, A CORPORATION OF NEW JERSEY.

DESIGN FOR A LOUD SPEAKER.

Application filed November 5, 1926. Serial No. 19,621. Term of patent 14 years.

To all whom it may concern:

Be it known that we, CLAIR L. FARRAND, residing at Forest Hills, N. Y., a citizen of the United States, ERNEST Ross, residing at East Orange, N. J., a citizen of the United States, and PAUL F. GODLEY, residing at Upper Montclair, N. J., a citizen of the United States, have invented a new, original, and ornamental Design for Loud Speaker, of which the following is a specification, reference being had to the accompanying drawings, forming a part thereof.

In the drawings, Fig. 1 is a front elevation, Fig. 2 is a rear elevation and Fig. 3 is a side elevation of the loud speaker.

We claim:

The ornamental design for a loud speaker substantially as shown.

In testimony whereof we have signed the foregoing specification.

CLAIR L. FARRAND.
PAUL F. GODLEY.
ERNEST ROSS.
